UNITED STATES PATENT OFFICE.

SAMUEL WATSON CHARLES, OF PALO ALTO, CALIFORNIA.

SAFETY-RAZOR.

1,216,944.

Specification of Letters Patent. Patented Feb. 20, 1917.

Application filed November 30, 1914. Serial No. 874,684.

To all whom it may concern:

Be it known that I, SAMUEL WATSON CHARLES, a citizen of the United States, residing at Palo Alto, in the county of Santa Clara and State of California, have invented a new and useful Safety-Razor, of which the following is a specification.

My invention relates to improvements in safety razors, in which the blade and guard are pivoted together in one end of the handle, and the opposite ends are held together or released at will by means of a latch at the end of the guard.

The object of my invention is to provide a razor of the same general form as is now used without a guard, with a guard and means whereby the razor blade and guard may be swung apart for cleaning and sharpening and the blade readily removed and re-placed.

These objects are attained by the device illustrated in the accompanying drawing, in which—

Figure 1 is a side view of a razor embodying the features of my invention, and showing the blade and guard swung out of alignment and in position for cleaning; Fig. 2 is another side view of the razor showing the guard swung into place over the blade and clamped by means of the latch in position for shaving; Fig. 3 is a section taken along the lines A—B and C—D of Fig. 2; and Fig. 4 is an enlarged section through the line E—F of Fig. 2. Fig. 5 is a sectional view on an enlarged scale through the pivotal connection and the immediate portions of the associated parts.

Similar figures refer to similar parts throughout the several views.

The razor blade 2 and guard 3 are pivoted together and to a suitable handle 1 by means of any suitable form of rivet 7, and may be folded into the handle when not in use.

I prefer to make this rivet of essentially the form shown in section in Fig. 3, so that by providing a suitable shoulder as shown, the guard 3 may be free to turn about part 7, but is held from coming off when thumb screw 8 is removed. By providing a removable thumb screw 8, which preferably is made to screw into rivet 7 as shown, so that rivet 7 is kept comparatively short in length, a means is provided for the easy removal of blade 2 by first removing screw 8, raising the leaf 10 of the handle 1 clear of rivet 7,

and swinging it about rivet 9 out of the way of the blade 2. The rivet 7 should be riveted tightly enough, or held by a suitably squared part, to prevent its turning with screw 8.

The leaf 10 of the handle 1 might preferably be made free to rotate about rivet 9 to facilitate the removal of the blade 2, though it is evident that this is not essential, provided leaf 10 is sufficiently flexible.

Blade 2 is preferably sharpened on both edges as shown more clearly in Fig. 4, and the guard 3 made to protect both edges, the edges of guard 3 being serrated as shown.

To clamp the guard 3 in position over the blade 2, a suitable latch is provided, which clamps the plane faces of the guard and razor blade together, and also prevents relative motion about the pivot 7. The latch used for illustration consists of the latch proper, 6, a coiled spring 5 for keeping the latch in position, and the part 4, riveted to guard 3, and serving as a guide for latch 6, and as a holder and stop for spring 5. Latch 6 is so bent as to engage the outer side of guard 3 and the outer side of blade 2, as shown in Fig. 3. Latch 6 also engages in a notch 11 in the end of blade 2.

For swinging blade 2 into and out of alignment with guard 3, and also to aid in holding the razor in shaving, the part forming the blade 2 is extended beyond the rivet 7 as shown.

To release the latch 6, the projecting end is pressed out of engagement with the notch 11 in blade 2, when the blade 2 and guard 3 may be swung out of alignment for cleaning. By properly shaping the end of blade 2 on either side of the notch 11 it acts as a cam in bringing blade 2 and guard 3 into alignment, moving catch 6 out of the way until opposite notch 11, when spring 5 forces it into the notch 11 locking guard and blade together ready for shaving.

Having described my invention, what I claim as new and desire to secure by Letters Patent is—

1. In a razor, the combination with a handle, of a razor blade member and a guard member, and a pivotal connection between the blade and guard members and the handle, said pivotal connection permitting the removal of one member while pivotally retaining the other member.

2. In a razor, the combination with a handle comprising separable sections, of a

pivot connecting the sections, a blade member, and a guard member mounted on the pivot between the handle sections, one of said members being removable from the pivot when the handle sections are separated.

3. In a razor, the combination with a handle comprising separable sections, of a pivot connecting the sections and having a shoulder, a guard mounted on the pivot between one handle section and the shoulder, and a blade mounted on the pivot between the guard and the other handle section.

4. In a razor, the combination with a handle comprising separable sections, of a pivot connecting the sections and having a

shoulder, a guard mounted on the pivot between one of the handle sections and the shoulder and retained thereby, a device detachably securing the other handle section to the pivot, and a blade mounted on the pivot between the guard and the other handle section and removable from said pivot when said latter handle section is disengaged therefrom.

In witness whereof I have hereunto set my signature in the presence of two subscribing witnesses this 24th day of November, 1914.

SAMUEL WATSON CHARLES.
